UNITED STATES PATENT OFFICE.

RALPH E. MARBURY, OF PITTSBURGH, PENNSYLVANIA, ASSIGNOR TO WESTINGHOUSE ELECTRIC & MANUFACTURING COMPANY, A CORPORATION OF PENNSYLVANIA.

LOUD-SPEAKING TELEPHONE.

Application filed November 28, 1923. Serial No. 677,584.

To all whom it may concern:

Be it known that I, RALPH E. MARBURY, a citizen of the United States, and a resident of Pittsburgh, in the county of Allegheny, and State of Pennsylvania, have invented a new and useful Improvement in Loud-Speaking Telephones, of which the following is a specification.

My invention relates to apparatus for the production of loud sounds.

Broadly speaking, the object of my invention is to produce sound of great volume corresponding to a relatively small vibratory electric current.

Another object of my invention is to produce an amplified sound corresponding to a vibratory electric current.

A further object of my invention is to amplify the energy of a vibratory electric current during the procedure of converting the vibratory electric-current energy into sound.

Another object of my invention is to supply energy for amplification of the energy contained in a vibratory electric current by the addition of further energy obtained from a mechanically rotating body.

In practicing my invention, I provide a diaphragm, a horn, a shaft and means for rotating it, an electromagnet for converting varying electric currents into a varying magnetic flux, and means under the control of the magnetic flux for producing a varying torque from the rotating shaft. I then vibrate the diaphragm by means of this varying torque, producing sound thereby, which sound is directed and controlled by the horn.

Other objects and structural details of my invention will be apparent from the following description when read in connection with the accompanying drawing, wherein:

The single figure is a diagrammatic sketch, partly in section, of my invention.

In the figure is shown a horn 1 attached to a supporting framework 2. Framework 2 carries a ring mount 3 in which is supported a diaphragm 4. Both horn and ring are carried on a support 5 which, in turn, is attached to a base plate 6. On the same base plate 6 is mounted an electric motor 7 having a shaft 8 and lead wires 9.

A friction drum 11 is mounted upon the shaft 8. A brake band 12 surrounds drum 11. An arm 13 is attached to brake band 12. A rod 14 connects the end of arm 13 to the

center of diaphragm 4. Armatures 15 and 16 are attached to brake band 12. An electromagnet 17 with a permanent magnet core 18 is positioned between armatures 15 and 16. Conductors 19 connected to electromagnet 17 lead to a source of vibratory electric-current energy. A case 21 surrounds and encloses the device.

The motor 7 may be of any substantially constant speed type and it may be adapted to run at any desired voltage, either alternating current or direct current.

In the operation of my device, I provide a suitable energy source for the motor 7, bringing it up to a speed which may desirably be above 500 revolutions per minute. The rated load capacity of motor 7 need not be greater than a few watts, since the actual power required for my device is small.

Conductors 19 are attached to the source of vibratory electric-current energy which it is desired to convert into sound. This may, if so desired, be the output of a radio detector system, or it may be a telephonic connection to any other source of vibratory electric current which it is desired to convert into sound. With the motor 7 running at normal speed and no current traversing conductors 19, a definite amount of friction occurs between drum 11 and brake band 12, by reason of the pull of permanent magnet core 18, which is substantially constant in value and produces a constant torque in the brake band. This constant torque is converted into a steady pull upon diaphragm 4 through the agency of arm 13 and rod 14. Accordingly, the diaphragm does not vibrate and no sound is produced.

A steady current flowing in conductors 19 will produce an increase or a decrease in the magnetic pull on the armatures 15 and 16, depending on the direction of the current. This will result in a change in the pressure of brake band 12 upon drum 11, thereby altering the torque developed and the pull upon the center of diaphragm 4, but no sound will be produced.

A vibratory current supplied to conductors 19 and coil 17 will, however, produce a varying attraction for armatures 15 and 16, thereby producing a varying amount of friction between brake band 12 and drum 11 and, in turn, producing a varying torque. This varying torque, in its turn, produces a varying pull upon the center of diaphragm 4.

If the vibratory current supplied to conductors 19 and coil 17 is of an audio frequency, the torque produced and transferred as a pull to the center of diaphragm 4 will vary at a corresponding audio frequency and will be perceived as a sound after passing through horn 1.

By means of my invention, it is possible to obtain a large amount of vibratory energy 10 conveyed to the center of diaphragm 4 in response to a smaller amount of vibratory electrical energy supplied to conductors 19. A considerable portion of the energy is obtained from the energy of rotation of shaft 8 15 and motor 9 and, therefore, is correspondingly supplied from the electrical input of leads 9.

In practice, this mechanism makes it possible to produce relatively loud sounds from 20 a relatively weak vibratory current.

While I have shown only one embodiment 25 of my invention in the accompanying drawings, it is capable of various changes and modifications without departing from the spirit thereof, and it is desired, therefore, that only such limitations shall be imposed thereon as are indicated in the prior art or in the appended claims.

I claim as my invention:

30 1. A loud speaking telephone device comprising a diaphragm, a horn, a rotating drum, a friction band on said drum, a projecting arm, attached to said band, a link between said diaphragm and said arm, armatures of magnetic material attached to the

ends of said band, an electromagnet adjacent to said armatures, and a source of signal frequency current connected to said magnet.

2. A sound reproducing device, comprising a horn, a diaphragm, and means for producing vibrations in said diaphragm, said means comprising a rotating drum, a friction band on said drum, means for converting the torque conveyed to said band into a pull on said diaphragm, and means comprising 40 armatures respectively attached to the ends of said band and an electromagnet operating therewith for varying the friction pressure between said drum and said band, and a source of variable electric current for 45 exciting said electromagnet.

3. In a sound-reproducing device, an exciting source of variable electric current, a constant-speed source of mechanical energy, means comprising a friction band and a 50 drum driven by said mechanical energy for obtaining a torque from said energy, means comprising a bar and link for converting said torque into a tangential pull, means comprising an electromagnet, and armatures 55 attached to said friction band for varying said torque in response to the variation in said exciting current, and means comprising a diaphragm and horn for converting the variations of said tangential pull into sound. 60

In testimony whereof, I have hereunto subscribed my name this 14th day of November, 1923.

RALPH E. MARBURY.
